UNITED STATES PATENT OFFICE.

WILLIAM A. AUMEN, OF WOODSBORO, MARYLAND, ASSIGNOR OF ONE-HALF
TO WILLIAM J. AYRES, OF WOODSBORO, MARYLAND.

WINDING-INDICATOR FOR TIMEPIECES.

SPECIFICATION forming part of Letters Patent No. 744,456, dated November 17, 1903.

Application filed February 10, 1903. Serial No. 142,743. (No model.)

To all whom it may concern:

Be it known that I, WILLIAM A. AUMEN, a citizen of the United States, residing at Woodsboro, in the county of Frederick and State of Maryland, have invented a new and useful Winding-Signal Attachment for Timepieces, of which the following is a specification.

My invention relates to signal attachments for timepieces; and it consists in the novel construction and combination of parts hereinafter described, and shown in the accompanying drawings.

The object of my invention is to improve devices of the class above mentioned by simplifying the operating mechanism thereof and by so arranging the parts thereof that the signal will be displayed some time before winding is absolutely necessary and after being exposed to view a considerable period will be withdrawn as the timepiece runs down, the special purpose of this action being to call attention to the immediate need of winding when the timepiece is nearly run down, and yet to give notice before that winding will soon be required.

In the drawings accompanying this specification, Figure 1 is a view in elevation of portions of the clock frame and face with my winding-signal and operating mechanism therefor attached, the parts being in the position assumed when the signal has just been displayed. Fig. 2 is a view, also in elevation, showing the parts in the position taken when the clock is completely wound. Fig. 3 is a view, also in elevation, showing the parts as they are when the clock is nearly run down and the signal is being gradually withdrawn.

In all of the above-mentioned figures corresponding parts are indicated by the same characters of reference throughout.

Referring to the drawings by reference characters, 1 represents the frame-supporting-operating mechanism of a timepiece. 2 designates the winding-post, having mounted on one end thereof a gear 3. The gear 3 meshes with a large gear 4, which carries rigidly mounted thereon a cam 6. This cam 6 and gear 4, which are made fast to each other, are loosely mounted to rotate on a rigid pin 5, which projects from a block 7. This

block 7 is attached by screws or other suitable means to the frame 1 at such points that the gear 4 will mesh with the gear 3, carried by the winding-posts of the timepiece. At the upper end of the block 7 is a projection 8, which has pivotally connected therewith an arm 9, at the free end of which is mounted a plate 10, bearing a suitable legend, such as "Wind me." When the pivoted arm 9 is in the position indicated in Fig. 1, the plate 10 is exposed to view through the slot 11 in the clock-face. Pivotally connected with the plate 10 at the end where it is joined to the pivoted arm 9 is a bifurcated pawl 12, normally held in the position shown in Fig. 1 by means of a spring 13. One of the prongs 14 on the pawl 12 is adapted to contact with the periphery of the cam 6 before the display of the winding-signal and the other 15 to contact therewith after the display of the winding-signal when it is being gradually withdrawn from view.

The operation of my winding attachment is as follows: The gears 3 and 4 are so proportioned that the number of turns of the winding-post 2 and gear 3 attached thereto required to completely wind the clock are sufficient to produce a single complete rotation of the gear-wheel 4, its shaft 5, and the cam carried thereby. When the clock is completely wound, the parts will all be in the position shown in Fig. 2, the plate 10 carrying the legend, which is displayed when it is desirable to wind the timepiece, being concealed from view behind the clock-face and the prong 14 of the pawl 12 being in contact with the cam 6 at the point marked A. As the clock gradually unwinds the gear 4 and the cam 6 are rotated in the direction indicated by the arrow, and when the prong 14 of the pawl passes the point B on the cam the pivoted arm 9 is allowed to drop downward under the influence of gravity, bringing with it the plate 10 and displaying the winding-signal through the slot 11 in the clock-face. This display of the winding-signal may be timed by suitably forming cam 6 to any desired interval before the clock is completely unwound. For example, the average one-day clock will run for thirty hours on one winding, and it is desirable to wind the clock when

- it has run about twenty-four hours, thus preventing the clock from running slow when the spring is nearly unwound. In clocks of this character, then, the time taken for the 5 pawl 12 to pass from the point A on the periphery of the cam to the point B as the clock unwinds would be twenty-four hours, and the time taken for the pawl to travel from the point B to the point A, which it would reach 10 again when the clock was completely unwound, should be about six hours. It is obvious that if the clock is designed to run for a longer time a proportionately greater interval between the display of the signal and 15 the complete unwinding of the clock may be provided by suitably proportioning the parts of the cam 6. Ordinarily in eight-day clocks it is desirable to have the signal displayed after the clock has run seven days, thus giving 20 a whole day's warning before the clock is completely unwound.
- It will be observed that after the prong 14 of the pawl passes the point B on the periphery of the cam and displays the signal for a 25 considerable period the pawl lies out of contact with the cam, the portion of the periphery of the cam then under the pawl being an arc on such short radius that the pawl is not long enough to reach it. After the signal 30 for winding has been displayed for a considerable period, however, this portion of the periphery of the cam passes from under the pawl and the prong 15 comes in contact with the portion of the periphery which forms the 35 rise from the arc on short radius to the arc on long radius with which the prong 14 contacts from the time the clock is completely wound until the signal for winding is displayed. During the time required for the 40 passage of the prong 15 up to the point A the signal is being gradually withdrawn, and if the clock is not wound before the prong 15 reaches the point A the unwinding will become complete and the clock will stop.
- 45 It will be observed that parts of my winding-signal attachment are few, that the attachment may be readily positioned on a clock without modifying any portion of the clock-works, and that action thereof is positive and 50 cannot be readily put out of order or prevented from operating in a proper manner.

By providing for the display of the winding-signal considerably before the clock is completely unwound any variation of the speed from being allowed to run while the tension 55 of the spring is very weak is prevented, and by providing for the gradual withdrawing of the signal as the time for winding grows shorter attention is a second time directed to the fact that winding is desirable if the signal has not already produced the desired result. 60

Having thus described my invention, what I claim as new, and desire to secure by Letters Patent, is—

1. The combination in a winding-signal attachment for timepieces of a pivoted arm, a signal carried thereby, a cam rotated by the unwinding of the timepiece, and a spring-pressed pawl pivotally mounted on said arm 70 and having its free end in contact with said cam.

2. The combination in a winding-signal attachment for a timepiece of a pivoted arm, a signal carried by said arm, a cam rotated by 75 the unwinding of the timepiece, and a pawl mounted on said arm and in contact with said cam, the cam being so formed that the pawl passes out of contact with the cam and permits the display of the winding-signal before winding is necessary, and again contacts with said cam to gradually withdraw the winding-signal from view before the timepiece is completely unwound. 80

3. The combination in a winding-signal attachment for timepieces of a pivoted arm, a signal carried thereby, a cam rotated by the unwinding of the timepiece, and a bifurcated pawl pivoted on said arm, one prong of said pawl being adapted to contact with the cam 90 before the display of the winding-signal and the other prong of the pawl being adapted to contact with the cam to withdraw the signal from view before the clock is completely unwound. 95

In testimony that I claim the foregoing as my own I have hereto affixed my signature in the presence of two witnesses.

WM. A. AUMEN.
